(57) **CLAIM**

The ornamental design for a camera with integral flash feature, as shown and described.

DESCRIPTION

The nature and intended use of the article in which the design is embodied is a photographic camera.

Reference is made to commonly assigned, co-pending U.S. applications Ser. No. 29/153,025 entitled Camera with Integral Flash Feature, filed Dec. 21, 2001, in the names of Anna C. Schelling, Robert J. Stanchus, Thomas E. Dussinger, and Anthony F. DiGaetano; Ser. No. 29/152,603 entitled Camera Covering, filed Dec. 21, 2001, in the names of Anna C. Schelling, Robert J. Stanchus, Thomas E. Dussinger, and Anthony F. DiGaetano.

FIG. 1 is a front, top, right-side, perspective view of a camera according to our new design;

FIG. 2 is a rear, bottom, left-side perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right-side elevation view thereof; and,

FIG. 8 is a left-side elevation view thereof.
